Cadmore & Co.

UNITED STATES PATENT OFFICE.

JOSEPH A. GRAY, OF CARROLLTOWN, PENNSYLVANIA.

LOCK.

SPECIFICATION forming part of Letters Patent No. 606,282, dated June 28, 1898.

Application filed June 25, 1897. Serial No. 642,308. (No model.)

To all whom it may concern:

Be it known that I, JOSEPH A. GRAY, a citizen of the United States, residing at Carrolltown, in the county of Cambria and State of Pennsylvania, have invented a new and useful Lock, of which the following is a specification.

My invention relates to locks, and particularly to a combined lock and latch of the gravity-actuated type wherein the use of springs is dispensed with, and both the bolt and the tumbler, whereby the bolt is locked in its extended position, are actuated solely by gravity, the tumbler being readily adjustable to release the bolt, and thus convert the device into a latch.

The objects of the invention are to provide a lock of the class named which shall be simple in construction, requiring the minimum number of parts to accomplish the necessary functions, and so arranged as to insure promptness and ease of operation and at the same time attain a degree of durability adapting it for use under the various conditions to which devices of this class are incident.

Further objects and advantages of this invention will appear in the following description, and the novel features thereof will be particularly pointed out in the appended claims.

In the drawings, Figure 1 is a front view of a lock constructed in accordance with my invention, the face-plate being omitted and the tumbler being shown in its disengaged position. Fig. 2 is a similar view showing the tumbler in position to lock the bolt when extended. Fig. 3 is a transverse section on the line 3-3 of Fig. 2. Fig. 4 is a detail view in perspective of the bolt detached.

Similar numerals of reference indicate corresponding parts in all the figures of the drawings.

The casing 1 may be adapted for arrangement either in a mortise or upon the surface of a closure, and within the same is disposed for longitudinal movement a bolt 2, of which the head 3 operates in a bolt-opening in the end of the casing. The shank of the bolt is provided with a longitudinal slot 4, which receives a fixed guide-pin 5 in the casing, and the rear end of the shank is constructed upon opposite sides with seats 6, formed by pairs of laterally-projecting lugs or ears 7. In one

of these seats is arranged the extremity of an operating-arm 8, extending in an approximately perpendicular position from an actuating-weight 9, said weight serving to yieldingly hold the free end of the operating-arm in its advanced position, (shown in Figs. 1 and 2,) and the hub of the operating-arm is fitted upon the knob-spindle 10. It will be seen that the bolt may be reversed in position to engage either of the seats 6 with the operating-arm, thus reversing the lock and adapting it for use upon either a right or a left hand door.

Arranged in operative relation with the bolt and preferably above the same is a tumbler mechanism which, in the construction illustrated, consists of a single tumbler 11, having at one end a longitudinal slot 12, fitted upon a guide-pin 13, and provided at the other or free end with a shoulder 14, adapted to engage with the bolt when said tumbler is in its depressed position. In the construction illustrated said shoulder engages the rear end of the bolt, and the tumbler is yieldingly held in its depressed position by gravity, inasmuch as the free end of the tumbler is enlarged or weighted. Furthermore, the tumbler is provided with an irregular limiting-slot, of which the body portion 15 is longitudinally disposed and which is provided with terminal upward extensions 16 and 17 of different lengths, and this limiting-slot receives a fixed limiting-pin 18, secured to the casing. When the tumbler is raised to bring the longitudinal or main portion of the slot into alignment with the limiting-pin, the tumbler may be moved longitudinally to bring either of the extensions 16 and 17 into alignment with the pin, and this transverse and longitudinal movement of the tumbler to accomplish said adjustments is attainable by means of a key-notch 19, formed in the under side of the tumbler contiguous to a key-hole 20 in the casing, the ward of the key being shown in dotted lines at 21 in Figs. 1 and 2. Obviously when the tumbler is adjusted to bring the longer extension 16 in alignment with the pin the tumbler is allowed to drop to bring its shoulder 14 into engagement with the bolt, and thus secure the bolt in its extended position, as indicated in Fig. 2, whereas when the tumbler has been adjusted to align the short extension 17 of the limiting-slot with

the pin 18 the downward movement of the free end of the tumbler is limited, and hence it is held out of engagement with the bolt.

- From the above description it will be seen that both the bolt and the tumbler are actuated by gravity and are yieldingly held in their operative positions by said force. It will be understood, furthermore, that while in the drawings I have illustrated but a single member in the tumbler mechanism a plurality of such members may be employed to increase the difficulty of operating the lock except by means of a special key provided for the purpose.
- In my lock the tumbler is mounted for differential movement with respect to the bolt, so that when the tumbler is moved to its advanced position it is raised and held out of the path of the bolt for the purpose of permitting the latter to be actuated by the knob-spindle and its weighted arm, whereby the bolt serves both as the latch and lock. This differential movement of the tumbler is important in that it is held out of the path of the bolt when the latter is to be actuated by the spindle, but when the tumbler is to be locked in its shot or projected position the tumbler is adapted to be lowered into engagement with the bolt and lock the latter against retraction under the influence of the spindle. In addition to the vertical differential movement relatively to the bolt the tumbler is also capable of a limited endwise movement parallel to the bolt, so that when the bolt is projected the tumbler may be moved into locking engagement therewith under the influence of the key-wards. It will be noted by reference to Fig. 1 that the tumbler is held in its raised position by the stud 17, fitting in the short extension of the slot 15, thus sustaining the shoulder 14 out of the path of the bolt and permitting the latter to operate freely when the spindle is turned; but when the bolt is projected in the position for locking the key is inserted in the lock and turned, so as to first lift the tumbler for the stud 17 to clear the slot extension 18 and then move the tumbler endwise for the stud to come opposite to the slot extension 16, whereupon the tumbler

drops by gravity for the stud 17 to enter the slot extension 16, and the locking-shoulder 14 drops in rear of the latch to lock the latter against retraction by the knob-spindle.

Various changes in the form, proportion, and the minor details of construction may be resorted to without departing from the spirit or sacrificing any of the advantages of this invention.

Having described my invention, what I claim is—

1. In a combined latch and lock, the combination with a spindle-controlled gravity-bolt, of a gravity-tumbler mounted above the bolt for differential vertical movement with respect thereto and having at one end a longitudinal guide-slot and at its enlarged end a longitudinal slot, 15, with extensions, 16, 18, of different lengths, a fixed stud playing in the guide-slot to permit the tumbler to have a swinging and sliding adjustment thereon, and another fixed stud playing in the slot, 15, to enter the short extension, 18, and sustain the tumbler in a position above and out of the path of the bolt, said tumbler having a locking-shoulder, 14, adapted to drop in rear of the bolt when the tumbler is moved to a position for the stud, 17, to enter the long extension, 16, of the slot, the whole combined and arranged for service, substantially as described.

2. In a combined latch and lock, the combination with a spindle-controlled gravity-bolt, of a gravity-tumbler mounted above the bolt for differential vertical movement with respect thereto, means for guiding and limiting both the horizontal and vertical movement of the tumbler, the latter being provided with a locking-shoulder adapted to drop in rear of the bolt, and means for sustaining the tumbler in a position above and out of the path of the bolt, all substantially as described.

In testimony that I claim the foregoing as my own I have hereto affixed my signature in the presence of two witnesses.

JOSEPH A. GRAY.
